[57] **ABSTRACT**

Promotion of aluminum hydrocarbyl synthesis by use of powder alloys of aluminum and lithium and aluminum and calcium.

10 Claims, 1 Drawing Figure

PATENTED DEC 10 1974

3,853,931

PRODUCTION OF HYDROCARBYL ALUMINUM HYDRIDES

BACKGROUND OF THE INVENTION

1. Field of the Invention

This invention relates to forming aluminum hydrocarbys, including hydrocarbyl aluminum hydrides and halides useful as catalysts, in alcohols for detergents, and in the production of olefins. More particularly, it relates to promotion of the reaction of aluminum with olefinic hydrocarbons or aluminum hydrocarbys and hydrogen.

2. Description of the Prior Art

U.S. Pat. No. 3,100,786 discloses use of sodium, lithium, potassium, cesium, rubidium, calcium, barium, strontium and magnesium in elemental amounts sufficient to activate aluminum used for reaction with an olefinic hydrocarbon and hydrogen to obtain an aluminum hydrocarbyl product. U.S. Pat. No. 3,104,252 teaches use of aluminum base powder alloys containing titanium, hafnium, zirconium, niobium, vanadium, uranium and scandium to provide improved reaction rates in the preparation of dialkylaluminum hydrides. While both of these procedures have been useful in aluminum hydrocarbyl production, a competing side reaction, hydrogenation, often wastes raw materials when olefin is present in the reacting medium, and the rate of reaction, in many instances, has not been as high as desired.

SUMMARY OF THE INVENTION

After extended investigation, I have found that use of powder alloys, preferably atomized powder, of aluminum with calcium, and aluminum with lithium, as promoters, catalysts or activators in reactions with aluminum hydrocarbys or olefins and hydrogen not only alleviates this side reaction problem but also substantially increases the efficiency of the hydrocarbylation reaction, particularly in the improved reactivity or rate of reaction. I prefer that the aluminum base alloy powder used according to the invention be preliminarily activated, for example, by ball milling powder produced by atomizing a melt of aluminum and calcium, or aluminum and lithium, or a melt of an aluminum-calcium alloy or aluminum-lithium alloy. The ball milling may be performed, for example, in a solution of triethylaluminum in an organic solvent such as benzene in an inert atmosphere.

When I refer herein to aluminum base alloys useful according to the invention, I include aluminum base alloys containing at least 98 percent by weight aluminum to which the alloying calcium or lithium has been deliberately added to the aluminum. The alloying elements can be added to the aluminum by any means known to those skilled in the art. Examples of metallurgical means by which the catalytic elements can be added include the following. (1) The elements can be added directly. (2) The elements, alloys, or inorganic salts can be added to the primary electrolysis cells. (3) Reductive compounds or mixtures of the elements can be added to the melting furnace.

Another way in which the alloying elements can be used is by blending aluminum base alloys containing a higher-than-necessary concentration of the alloying elements with aluminum or aluminum base alloys containing none, or less than a reaction-promoting amount, of the alloying elements.

Aluminum hydrocarbyl compounds which may be reacted and prepared using lithium and calcium-containing aluminum base powder alloy promoters according to the invention include aluminumalkyl, aryl, aralkyl and alkaryl hydrides and halides which may be represented by the formula

wherein R₁ is a hydrocarbon radical and R₂ and R₃ hydrogen, halogen or a hydrocarbon radical. The hydrocarbon radical can contain from two to 40 carbon atoms and can be alkyl, aryl, alkaryl or aralkyl.

The calcium and lithium-containing aluminum base alloys used according to my invention are suitable for preparation of organoaluminum compounds such as the following:

30 Diethylaluminum chloride
Diethylaluminum bromide
Diisobutylaluminum chloride
Diisobutylaluminum bromide
Diocetylaluminum chloride
Dipentadecylaluminum bromide
Didocosylaluminum chloride
Diphenylaluminum hydride
Di-para-tertiarybutylphenyl aluminum hydride
Diphenyloctylaluminum hydride
Diphenyloctylaluminum chloride
Triphenyloctylaluminum
35 Diethylaluminum hydride
Diisobutylaluminum
Diocetylaluminum hydride
Dipentadecylaluminum hydride
Didocosylaluminum hydride
Ditetracontylaluminum
Triethylaluminum
30 Triisobutylaluminum
Triocetylaluminum
Tripentadecylaluminum
Tridocosylaluminum

40 Representative starting aluminum carbonyl compounds or olefins useful in reacting with powdered aluminum alloyed with lithium and calcium according to the invention correspond more or less to the organic radical or hydrocarbon portions of the above-recited formula and specific compounds.

45 The use of the term olefin herein is intended to include hydrocarbons having ethylenic unsaturation such as ethylene, propylene, butadiene and styrene.

50 The reaction promoted by calcium and lithium-containing aluminum base alloys according to the invention, using triethylaluminum (TEA) as representative of aluminum hydrocarbys which may be reacted with hydrogen to form the corresponding hydride, may be represented as follows:

The diethylaluminum hydride can then be reacted with ethylene to produce triethylaluminum as follows:

65 Representative of starting materials which may be reacted according to the foregoing hydrocarbyl reactions employing lithium and calcium-containing powder al-

loys are triethylaluminum (TEA), triisobutylaluminum (TIBA), trioctylaluminum, tripentadecylaluminum, and tridocosylaluminum. Commercially available triethylaluminum useful as the starting TEA reacted as above to yield additional TEA may also contain some tri-n-propylaluminum, tri-n-butylaluminum, triisobutylaluminum hydride and methane or other residual solvent. The olefin used in forming the desired aluminum hydrocarbyl may be reacted directly with the lithium or calcium-containing aluminum base alloy and hydrogen, if desired, instead of using an aluminum hydrocarbyl compound at the start of the reaction.

The particulate aluminum base alloys containing lithium or calcium employed according to the invention include atomized aluminum, granulated aluminum, powdered aluminum, aluminum powder, or any other type of aluminum particles fine enough to be wet milled or ground, for example, in a ball mill. The particle size is not critical according to the invention. Preferred milling, when the aluminum base alloy is activated by milling, is in the presence of an inert hydrocarbon such as benzene, hexane, mineral spirits or the like. Time used when milling is employed for activating the aluminum base alloy powder is not critical according to the invention, although only a few seconds are required to impart the desired activity. Nor are the temperature and pressure during the milling critical, ambient temperature and pressure being satisfactory.

Representative particulate aluminum base alloy powder the hydrocarbyl reaction of which is conducted according to the invention has the following representative particle-size breakdown (U.S. Sieve Series).

MESH	WEIGHT %
+12	0.0
-12+40	11.8
-40+100	26.6
-100+200	18.6
-200+325	13.6
-325	29.4

Generally, the reaction of the aluminum hydrocarbyl or olefin and hydrogen with the calcium or lithium-containing aluminum base alloy is conducted at a temperature of 80° to 200° C, preferably 100° to 150° C, and at a pressure of 60 to 350 atmospheres. The reaction will occur at a mole ratio of aluminum base alloy to aluminum hydrocarbyl of from 0.1:1 to 10:1. I have reacted 20g (0.74 mole) of the calcium or lithium. The experimental parameters were those set out immediately above.

containing aluminum base alloy, 325 ml triethylaluminum (2.38 moles) and 2,000 psi hydrogen (about 2.5 moles). As little as about 0.1 percent by weight of the alloying calcium or lithium is effective according to the invention.

BRIEF DESCRIPTION OF THE DRAWING

The drawing is a graph plotting reaction time in minutes against hydrogen (H₂) pressure decrease during the reaction (psi) and showing the improved reaction rate, using calcium-containing and lithium-containing aluminum base alloys according to the invention, in terms of pressure drop per unit time, psi/sec (slope) over that for substantially pure aluminum (base metal, commercial purity) and for high purity aluminum. The value of the slope indicated in the drawing for each curve was taken from the steepest portion of the curve.

DESCRIPTION OF THE PREFERRED EMBODIMENTS

The following examples are illustrative of the invention.

EXAMPLE 1

In the following table (I), the initial reaction rate following induction for an aluminum base alloy containing calcium and one containing lithium is compared to that for 99.99 percent aluminum and other alloys, for example, those containing metals shown useful in elemental form by the aforementioned U.S. Pat. No. 3,100,786 in the reaction of triethylaluminum and hydrogen. For the alloys shown in Table I, if no reaction took place within 60 minutes, as indicated by H₂ pressure drop, the testing was discontinued. Otherwise, the reaction was continued until measurement of an initial reaction rate. Reaction rate was measured by the H₂ pressure drop per unit time (psi/sec). For the lithium/aluminum alloy in both instances the tabulated value is the average of two runs.

The reaction was conducted in an autoclave at 120° C at a pressure 2,000 psi hydrogen (about 2.5 moles) in the presence of 20g aluminum or aluminum base alloy (0.74 mole) and 325 ml commercial purity triethylaluminum (2.38 moles). The reaction is believed to be as follows:

The atomized powder (20g of Al) was ball milled in 4 ml of triethylaluminum and 146 ml of benzene prior to use in the reaction.

TABLE I

Alloying Constituent	Concentration	Initial Reaction Rate (Following Induction) psi/sec.	Induction Period min.
Ti	0.2	1.6	1 (less than)
Mn	4.0	0.46	4
Mo	8.0	0.36	5
Fe	3.0	0.29	17
Co	1.6	0.23	31
La	0.2	0.22	24
Sr	2.0	0.18	32
Rare Earths	0.005	0.11	47
Mischmetal	0.005	0.08	54
W	1.0	0.08	36
Cr	0.2	0.07	50
None	99.99 Al	Test stopped, no reaction	60
B	0.1	Test stopped, no reaction	60
B	3.0	Test stopped, no reaction	60
Mg	1.0	Test stopped, no reaction	60
Be	1.0	Test stopped, no reaction	60
Zn	5.0	Test stopped, no reaction	60
Li	0.2	0.32	13
Ca	0.2	0.20	26

EXAMPLE 2

This example illustrates the advantage of using Al/Li and Al/Ca powder alloys according to this invention over using physical mixtures of Al with Li and Al with Ca. Table II records the rate of reaction in synthesizing dialkylaluminum hydride from trialkylaluminum according to the equation set out hereinabove.

solved, assuming that only reactions (2), (3) and (4) occurred. This quantity, as a percentage of the aluminum initially charged to the autoclave, was compared with the aluminum found to be actually dissolved in the liquid medium, after separation of the unreacted solids. Any discrepancy between these two figures is thought to be an index to the extent that reaction (1) occurred. The data are summarized in Table III.

TABLE III

Metal or Alloying Element	Amount of Alloying Element % by Weight	Induction Period min.	Initial Rate Hydrogen Consumption psi/sec.	Dissolved Aluminum	
				Calc. from H ₂ Consumed %	Actually Found %
Al ¹	—	18	0.20	78	56
Ca	0.16	11	0.33	69	76
Li	0.26	3	0.37	76	77
Ti	0.20	0	0.77	170	80

¹Commercial-Purity Aluminum Atomized Powder

The reaction occurred under substantially the same conditions as those in Example 1 except that a different lot of TEA was used.

Table II

	In Alloy Form	Simple Addition to Mill
Calcium		
Induction Period	30 min.	59 min.
Reaction Rate	0.19 psi/sec.	0.10 psi/sec.
Lithium		
Induction Period	8 min.	36 min.
Reaction Rate	0.79 psi/sec.	0.11 psi/sec.

EXAMPLE 3

20g (0.74 mole) of the aluminum or aluminum base alloys shown in Table III hereinbelow were activated by milling in the presence of a benzene solution containing 0.04 mole triethylaluminum per mole aluminum. The activated slurry was transferred to a 1-liter autoclave, to which 475 ml 1-octene (2.9 moles) were added. The autoclave was heated to 120° C. After temperature equilibrium had been reached, 2,000 psi hydrogen was pressed in. Gas pressure inside the autoclave was monitored continuously as a function of time. Competing reactions are thought to have consumed hydrogen according to the following schemes,

where C₈H₁₆ is 1-octene, and C₈H₁₈ is octane. Diocetylaluminum hydride present in the reacting mixture reacts with 1-octene according to the equation

as long as 1-octene is present in the system.

Overall rate of reaction was calculated as psi hydrogen consumed per second. The total amount of hydrogen consumed was used to calculate the theoretical amount of aluminum base alloy that should be dis-

25 The data in Table III show promotion by calcium and lithium-containing aluminum base alloys of conversion of 1-octene to aluminum hydrocarbyl compounds, with no appreciable loss of 1-octene through side reaction by hydrogenation. The data also confirm that such loss of 1-octene does, however, occur when prior art commercial-purity aluminum is used, and in a major proportion when prior art titanium-containing aluminum base alloy is employed.

30 While the invention has been described in terms of preferred embodiments, the claims appended hereto are intended to encompass all embodiments which fall within the spirit of the invention.

35 Having thus described my invention and certain preferred embodiments thereof, I claim:

40 1. In a process for reacting aluminum with hydrogen and an olefin or aluminum hydrocarbyl compound, the improvement which comprises reacting the hydrogen and the olefin or aluminum hydrocarbyl compound with an aluminum base alloy powder containing at least 98 percent by weight aluminum and 0.1-2.0 percent by weight lithium, thereby increasing the reactivity of the aluminum.

45 2. The improvement of claim 1 wherein the reaction is conducted at a temperature of from about 80° C to about 200° C and at a pressure of from about 60 atmospheres to about 350 atmospheres.

50 3. The improvement of claim 1 wherein the hydrogen and the aluminum hydrocarbyl or olefin are present in excess.

55 4. The improvement of claim 1 wherein the mole ratio of aluminum base alloy to aluminum hydrocarbyl or olefin is from about 0.1:1 to about 10:1.

5. The improvement of claim 1 wherein the aluminum base alloy powder is activated by ball milling in the presence of an inert hydrocarbon prior to said reacting.

6. The improvement of claim 1 wherein the aluminum base alloy powder comprises atomized powder.

7. The improvement of claim 1 wherein the aluminum hydrocarbyl compound has the formula

wherein R_1 is a hydrocarbon radical and R_2 and R_3 are hydrogen, halogen or a hydrocarbon radical, said hydrocarbon radical containing from two to 40 carbon atoms and being alkyl, aryl, alkaryl or aralkyl.

8. The improvement of claim 1 wherein at least one compound selected from the group consisting of an aluminum hydrocarbyl, an aluminum hydrocarbyl hydride and an aluminum hydrocarbyl halide is formed having the formula

wherein R_1 is a hydrocarbon radical and R_2 and R_3 are hydrogen, halogen or a hydrocarbon radical, said hy-

drocarbon radical containing from two to 40 carbon atoms and being alkyl, aryl, alkaryl or aralkyl.

9. In a process for reacting aluminum with hydrogen and an olefin or aluminum hydrocarbyl compound, the improvement which comprises reacting the hydrogen and the olefin or aluminum hydrocarbyl compound with a powder selected from the class consisting of a lithium-aluminum alloy and a calcium-aluminum alloy wherein the amount of lithium or calcium in the alloy

10 is from about 0.1 to about 2 percent by weight of the alloy, thereby increasing the reactivity of the aluminum.

10. The process of claim 9 wherein the aluminum content of said lithium-aluminum or calcium-aluminum alloys is at least 98 percent by weight.
